AUTOMATIC HYDRAULIC BRAKE

Charles A. Green, Washington, D. C., and Ernest
M. Seifert, Brooklyn Park, Md.

Application January 12, 1938, Serial No. 184,592

12 Claims. (Cl. 114—239)

(Granted under the act of March 3, 1883, as
amended April 30, 1928; 370 O. G. 757)

1

This invention relates to means for preventing whipping of torpedo tubes when a torpedo is fired and has among its several objects:

To provide automatically acting means to prevent displacement of torpedo tubes from their position to direct a torpedo to a target;

To provide means actuated by the pressure of the agent utilized to expel a torpedo from a torpedo tube to lock the tube in the desired firing position;

To provide simple and highly effective mechanism for the purpose mentioned that is not likely to get out of order and will not fail to function.

In the drawings:

Fig. 1 is a top plan view of quadruple torpedo tubes with portions of the tubes cut away to show certain parts of the present invention;

Fig. 2 is a side elevation of the parts shown in Fig. 1;

Fig. 3 is an enlarged detail plan view, with parts in section, of the valve actuating means;

Fig. 4 is an elevational view, with parts in section, of the valve and means for operating the same;

Fig. 5 is a transverse sectional view taken on the line 5—5, Fig. 4;

Fig. 6 is an axial sectional view of the pressure operated means, substantially on the line 6—6, Fig. 2;

Fig. 7 is an elevational view of the part shown in Fig. 6.

It is well known that firing a torpedo from a torpedo tube results in whipping or displacement in train, of the tube, with resultant inaccuracy in fire and failure to direct the torpedo accurately to its target. The present invention is a simple and very satisfactory solution of the problem of preventing this undesirable displacement.

While our invention is shown and described in association with quadruple torpedo tubes, it is to be understood that its usefulness is not limited thereto but may be used with one or more on a common mount. It is of course obvious that firing a torpedo from a tube which is displaced radially from the center of the mount about which it is trained will develop a torque tending to rotate the mount and consequently our invention is of greater value in connection with a multiple mount of tubes, but it may be used with triple, double or even, if desired, with single tubes.

In the drawings are shown four torpedo tubes 8 on a mount 9 whereon the tubes may be trained. The training mechanism is a worm 10 carried

in a hanger 11 fixed to the tubes and meshed with a gear 12 that is fixed against rotation by key 13 whereby, when shaft 14 to which worm 10 is secured is driven by a motor (not shown) the tubes will be caused to move in azimuth.

A coupling 15 connects shaft 14 to the shaft 16 of a hydraulic device 17 of well-known construction such as is commonly called the "B" end of a hydraulic variable speed gear whereby rotation of shaft 14 will drive the device 17 and cause circulation of fluid therethrough in a manner well-known. Pipes 18 and 19 are connected, through valve casing 20 to constitute, with the device 17, a closed circuit in which fluid is circulated by rotation of shaft 14. The valve casing 20 encloses a quick closing valve 21 (Fig. 4) consisting of a cylindrical valve member 21 having through it a passage 22 that is adapted to be aligned with the openings from pipes 18 and 19 into the valve casing when in open position but is turned at right angles to the line connecting said openings when in the closed position, thereby preventing passage of fluid through the above mentioned closed hydraulic circuit. It is obvious that when valve 21 is in the closed position the circulation of fluid through the device 17 will be prevented and thereby the shaft 14 will be held against rotation. Consequently, torque applied to rotate the tubes 8 on their mount will be prevented from becoming effective to set up such rotation. The device 17 is fixed to the torpedo tube 8 by means of a hanger bracket 23.

Fixed to the spindle 24 of valve 21 is a lever arm 25 having on it an upwardly projecting pin 26 slidably disposed in slot 27 in a head 28 carried by piston rod 29. The piston rod 29 is engaged with a piston 30 in cylinder 31 that is connected by pipe 32 to a manifold 33 operatively connected to the cylinders 34 to place the cylinders 34 in communication with cylinder 31. The spring 35 in cylinder 34 is under compression and tends to hold the cylinder 30 in the position depicted in Fig. 3 whereby the valve 21 is normally maintained in the open position.

Slidably disposed in each cylinder 34 is a piston 36 that is normally held at the limit of its movement toward the tube 8 upon which the cylinder 34 is mounted by a spring 37. The space above piston 36 is filled with oil or other suitable fluid that forms a part of the fluid body filling the pipe 32 and the manifold 33, whereby pressure exerted upon the piston 36 to move it upwardly in its cylinder will be transmitted to piston 30 to move piston 30 outwardly and thereby, through lever arm 25, rotate the valve 21 to

the closed position. The lower end of piston 36 has a cavity 38 formed in it in registry with the passage 39 that places cylinder 34 in communication with the interior of the tube 8. A vent 40 is provided to permit free passage of air for the purpose of preventing back pressure that would tend to check the movement of piston 36. A reservoir 41 is connected to manifold 33 through a check valve 43 of any well-known construction that will permit fluid from 41 to keep the pressure system continuously filled with fluid but will prevent passage of fluid from said system back to the reservoir 41 when the fluid in the system is under operating pressure.

The firing mechanism 43 is shown as being of the type utilizing a charge of powder but our invention is adapted for use with compressed air or any type of expansible agent used to expel the torpedo from the tube. It will be obvious from the foregoing that when the pressure in tube 8 is increased to expel a torpedo therefrom, that pressure will act through the passage 39 to force piston 36 upwardly against the action of spring 37, thereby displacing fluid from the cylinder 34 and transmitting through the manifold 33 and pipe 32 a volume of fluid that will force the piston 30 outwardly from its normal position and actuate the valve 21 to the closed position thereby preventing circulation of fluid through the device 17 and pipes 18 and 19, which will apply an effective hydraulic lock to shaft 14 and hold it positively against rotation whereby any displacement of the tube in train is absolutely prevented. The action of our invention is substantially instantaneous, is effective before the pressure in the tube is sufficient to break the stop box tension link, locks the torpedo tube against whipping when a torpedo is being fired but promptly releases after the torpedo has left the tube so the tube may be immediately moved in train to direct it upon any other target if so desired.

According to the provisions of the patent statutes we have set forth the principle and mode of operation of our invention and have illustrated and described what we now consider to represent its best embodiment. However, we desire to have it understood that within the scope of the appended claims the invention may be practiced otherwise than as specifically illustrated and described.

The invention herein described and claimed may be used and/or manufactured by or for the Government of the United States of America for governmental purposes without the payment of any royalties thereon or therefor.

We claim:

1. The combination with a torpedo tube mounted to be movable in train, training mechanism therefor including a rotatable shaft positively connected to drive said tube in train, and means to introduce into said tube a fluid propulsive agent to expel a torpedo therefrom, of a device having a part connected to said shaft to rotate therewith, fluid circulating means driven by said part, a conduit connected to convey fluid from the discharge to the intake of said circulating means, a quick shut-off rotary valve in said conduit to control the flow of fluid therethrough, a first cylinder, a first piston therein, means operatively connecting said piston to operate said valve, resilient means acting upon said piston to hold said valve normally open, a second cylinder having one end in communication with the interior of said tube adjacent the point of admission of said agent, a second piston in said second cylinder movable away from said tube by the pressure of said agent, resilient means normally holding said second piston at the limit of its movement toward said tube, a fluid system connecting said cylinders to each other whereby movement of said second piston by said agent is transmitted to said first piston to move said valve to the closed position and prevent circulation of fluid through said conduit, a container connected to said system to supply fluid thereto, and means to prevent return of fluid from said system to said container.

2. The combination with a torpedo tube mounted to be movable in train, training mechanism therefor including a rotatable shaft positively connected to drive said tube in train, and means to introduce into said tube a fluid propulsive agent to expel a torpedo therefrom, of a device having a part connected to said shaft to rotate therewith, a fluid circulating means driven by said part, a conduit connected to convey fluid from the discharge to the intake of said circulating means, control means in said conduit to control the flow of fluid therethrough, a first cylinder, a first piston therein, means operatively connecting said piston to operate said control means, resilient means acting upon said piston to hold said control means normally open, a second cylinder having one end in communication with the interior of said tube adjacent the point of admission of said agent, a second piston in said second cylinder movable away from said tube by the pressure of said agent, resilient means normally holding said second piston at the limit of its movement toward said tube, a fluid system connecting said cylinders to each other whereby movement of said second piston by said agent is transmitted to said first piston to move said valve to the closed position and prevent circulation of fluid through said conduit, a container connected to said system to supply fluid thereto, and means to prevent return of fluid from said system to said container.

3. The combination with a torpedo tube mounted to be movable in train, training mechanism therefor including a rotatable shaft positively connected to drive said tube in train, and means to introduce into said tube a fluid propulsive agent to expel a torpedo therefrom, of a device having a part connected to said shaft to rotate therewith, fluid circulating means driven by said part, a conduit connected to convey fluid from the discharge to the intake of said circulating means, a quick shut-off rotary valve in said conduit to control the flow of fluid therethrough, a first cylinder, a first piston therein, means operatively connecting said piston to operate said valve, resilient means acting upon said piston to hold said valve normally open, a second cylinder having one end in communication with the interior of said tube adjacent the point of admission of said agent, a second piston in said second cylinder movable away from said tube by the pressure of said agent, resilient means normally holding said second piston at the limit of its movement toward said tube, and operative connecting means whereby movement of said second piston effects corresponding actuation of said first piston to move said valve to the closed position and prevent circulation of fluid through said conduit.

4. The combination with a torpedo tube mounted to be movable in train, training mecha-

75

nism therefor including a rotatable shaft positively connected to drive said tube in train, and means to introduce into said tube a fluid propulsive agent to expel a torpedo therefrom, of a device having a part connected to said shaft to rotate therewith, fluid circulating means driven by said part, a conduit connected to convey fluid from the discharge to the intake of said circulating means, control means in said conduit to control the flow of fluid therefrom, a first cylinder, a first piston therein, means operatively connecting said piston to operate said control means, resilient means acting upon said piston to hold said control means normally open, a second cylinder having one end in communication with the interior of said tube adjacent the point of admission of said agent, a second piston in said second cylinder movable away from said tube by the pressure of said agent, resilient means normally holding said second piston at the limit of its movement toward said tube, and operative connecting means whereby movement of said second piston effects corresponding actuation of said first piston to move said control means to the closed position and prevent circulation of fluid through said conduit.

5. The combination with a tubular member mounted to be rotatable about an axis transverse to the length of said member, means including a rotatable shaft positively connected to drive said member in rotation, and means to produce an increase of pressure in said member, of a device having a part connected to said shaft to rotate therewith, means driven by said part to propel a stream of fluid, a conduit associated with the last mentioned means to constitute therewith a closed circuit for said fluid, control means in said conduit to control the flow of fluid therethrough, a first cylinder, a first piston therein, means operatively connecting said piston to operate said control means, means acting to hold said control means normally open, a second cylinder in communication with the interior of said tubular member, a second cylinder movable away from the tubular member by pressure therein, means normally holding said second piston toward said tubular member, and a fluid system connecting said cylinders with each other whereby movement of said second piston by said pressure is transmitted to said first piston to move said control means to the closed position and prevent circulation of fluid in said conduit.

6. The combination with a tubular member mounted to be rotatable about an axis transverse to the length of said member, means including a rotatable shaft positively connected to drive said member in rotation, and means to produce an increase of pressure in said member, of a device having a part connected to said shaft to rotate therewith, means driven by said part to propel a stream of fluid, a conduit associated with the last mentioned means to constitute therewith a closed circuit for said fluid, control means in said conduit to control the flow of fluid therethrough, a first cylinder, a first piston therein, means operatively connecting said piston to operate said control means, means acting to hold said control means normally open, a second cylinder in communication with the interior of said tubular member, a second piston in said second cylinder movable away from the tubular member by pressure therein, means normally holding said second piston toward said tubular member, and operative connecting means whereby movement of said second piston effects corresponding actu-

ation of said first piston to move said control means to the closed position and prevent circulation of fluid through said conduit.

7. The combination with a torpedo tube mounted to be movable in train, training mechanism therefor including a rotatable shaft positively connected to drive said tube in train, and means to introduce into said tube a fluid propulsive agent to expel a torpedo therefrom, of a device having a part connected to said shaft to rotate therewith, fluid circulating means driven by said part, a conduit connected to convey fluid from the discharge to the intake of said circulating means, control means in said conduit to control the flow of fluid therethrough, a first cylinder, a first piston therein, means operatively connecting said piston to operate said control means, means acting upon said piston to hold said control means normally open, a second cylinder having one end in communication with the interior of said tube adjacent the point of admission of said agent, a second piston in said second cylinder movable away from said tube by the pressure of said agent, means normally holding said second piston at the limit of its movement toward said tube, and operative connecting means whereby movement of said second piston effects corresponding actuation of said first piston to move said control means to the closed position and prevent circulation of fluid through said conduit.

8. The combination with a tubular member mounted to be rotatable about an axis transverse to the length of said member, means including a rotatable shaft positively connected to drive said member in rotation, and means to produce an increase of pressure in said member, of a device having a part connected to said shaft to rotate therewith, means driven by said part to propel a stream of fluid, a conduit associated with the last mentioned means to constitute therewith a closed circuit for said fluid, control means in said conduit to control the flow of fluid therethrough, means actuatable by pressure in said tubular member, means to transmit movement of said piston at the limit of its movement toward said tube, and operative connecting means whereby movement of said second piston effects corresponding actuation of said first piston to move said control means to the closed position and prevent circulation of fluid through said conduit.

9. The combination with a rotatably mounted hollow member, and means including a rotatable shaft positively connected to drive the same in rotation, of a closed hydraulic circuit including means to propel fluid through said circuit and means to control the flow of fluid therethrough, a movable member connected to actuate said control means to closed position to prevent said flow of fluid, means responsive to pressure in said hollow member operatively connected to move said movable member to close said control means, and means acting to hold said control means in normally open position.

10. The combination with a rotatably mounted hollow member, and means including a rotatable shaft positively connected to drive the same in rotation, of a closed hydraulic circuit including means to propel fluid through said circuit and means to control the flow of fluid therethrough, and mechanism actuatable by pressure in said hollow member to prevent said flow of fluid and thereby hydraulically lock said hollow member against rotation.

11. The combination with a torpedo tube and means to rotate the same, of a hydraulic device driven by said means, means to prevent the flow of fluid through said device, and means actu-

able by pressure in said tube when a torpedo is fired to operate said flow preventing means and thereby hydraulically lock said tube against whipping.

12. The combination with a rotatably mounted 5 hollow device adapted to discharge missiles by

increase of pressure in said device, of means to drive said device in rotation, and means actuated by increase of pressure in said device to lock said device against whipping.

CHARLES A. GREEN.
ERNEST M. SEIFERT.
